PAUL A. BANCEL, OF MONTCLAIR, NEW JERSEY, ASSIGNOR TO INGERSOLL-RAND COMPANY, OF JERSEY CITY, NEW JERSEY, A CORPORATION OF NEW JERSEY

CONDENSER

Application filed August 11, 1932. Serial No. 628,286.

This invention relates to surface condensers and more particularly to a surface condenser in the construction of which means have been provided to render inoperative a portion of the cooling surface thereof, and to operate on the remaining portion or portions.

The principal object of this construction is to permit operation of a steam power unit in spite of a leakage condition in the condenser which would ordinarily require the shutting down of the unit or tolerate contamination of the condensate. An incidental object of the invention is to permit ready access to the cooling tubes for the purpose of repair or cleaning during the operation of the major part of the condenser.

The construction of a condenser according to my invention is admittedly more expensive in first cost than in a condenser of conventional design, but in cases where cooling water of very impure character such as is drawn from certain rivers must be used, it may be cheaper from an operative standpoint to employ a condenser of the proposed type.

Salt water and acid bearing water has an extremely corrosive action upon copper or brass tubing, and it is not at all unusual for tubes to become so corroded that they leak cooling water into the condenser thereby polluting the condensate and rendering it unfit for use as feed water. When such a condition arises it becomes necessary to shut down the unit in which such leakage occurs as soon as is practicable in order to prevent serious damage to the boiler and other important units of the steam power equipment.

The drawing illustrates a longitudinal, sectional view of a surface condenser to which my invention has been applied. A condenser shell 10 is closed at one end by an inlet water box 11 and at the other end by an outlet water box 12. Intermediate the ends of the condenser shell and the water boxes are placed tube sheets 28 to receive the ends of cooling tubes 24 which traverse the condenser. The water boxes 11 and 12 are divided into sections 13 and 14 respectively by horizontal partitions 26.

Water is introduced to each of the sections

13 by inlet water mains 15 controlled by valves 18 and the circulating water, after passing through the tubes, is removed from the water box sections 14 through water mains 16 controlled by valves 19. Between each outlet water box and its valve 19 is connected a pipe 17 controlled by a valve 20 which communicates with an arm of a manifold 21 which runs to a discharge pump 22. Condensate may be removed from the condenser by any suitable means (not shown) through an opening 23 in its base.

At the top of each inlet water box section 13 is an aperture 27 to which is connected an individual steam ejector 25 of conventional design. The operation of these ejectors may be controlled by valves such as the valve 29 which is shown connected to the uppermost ejector 25.

In operation exhaust steam from a turbine or other power unit enters the condenser through an exhaust nozzle 30 and is condensed by contact with the cooling tubes 24 and the condensate is withdrawn through the opening 23. A suitable vacuum is maintained in the condenser by air removal apparatus (not shown).

Owing to the fact that the entire interior of the condenser is maintained under a comparatively high vacuum during operation and the water in the cooling tubes is under a relatively high head, a leak in one of the tubes 24 is bound to result in a considerable volume of water at high velocity spraying into the condenser and contaminating the condensate therein. Should a like condition arise in a condenser of ordinary construction it would be necessary as explained above to shut down the condenser and its associated apparatus as soon as possible in order to prevent damage. In my preferred construction, however, it would not be necessary to take the entire condenser out of service, but only to shut down that section in which the leak occurred thus permitting the continued operation of the power unit under a slightly increased back pressure.

Assuming that the leak occurred in one of the tubes connecting the uppermost water box sections 13 and 14 it would be necessary to

close the valve 18 controlling section 13 to prevent any more water being forced into that particular part of the circulating system. With the valve 18 closed, however, and the 5 valve 19 open the water remaining in the tubes would not run out through the valve 19 unless it was placed under sufficient suction to overcome the vacuum created by its removal. As it is unusual to have a pump to withdraw water from the circulating system of a condenser provision has been made by means of pump 22 and its piping and valve system, namely, the manifold 21, the valves 20 and the communicating pipes 17 to remove 10 water from any section which may be shut down or cut out. By closing the uppermost valve 19, opening the uppermost valve 20 and placing pump 22 in operation the water remaining in the leaky part of the system would 15 speedily be removed and the remaining portions of the condenser would then carry the full load. In order to overcome any loss of vacuum which might be occasioned by air leakage through the section of the condenser 20 which has been shut down its respective ejector 25 may be put into operation to place the disconnected cooling section under a vacuum.

Should a leak occur in any of the other 25 tubes of the condenser, a similar procedure would be followed. With suitable handholes (not shown) in the water box sections 13 and 14 tubes may be cleaned or changed while the condenser is in operation.

30 Frequently it is desirable, in order to obtain the greatest efficiency in a condenser, to maintain a higher velocity of flow of cool-

ing water in the upper tubes of a condenser, and it will be obvious that a construction of the type described lends itself readily to such regulation simply by means of the throttling effect obtainable by suitable operation of 70 the valves 18.

I claim:

1. A surface condenser comprising an inlet 75 for steam, a tube nest divided into a plurality of groups of tubes, water boxes communicating with each group of tubes, means selectively to supply circulating cooling water to each group of tubes, and pump means for withdrawing water from any group of tubes.

2. A surface condenser comprising an inlet 80 for steam, a tube nest divided into a plurality of groups of tubes, water boxes communicating with each group of tubes, piping to circulate cooling water through each group of tubes, valves in said piping to regulate the 85 flow of water through any group of tubes, and pump means associated with said piping to withdraw cooling water from any group of tubes.

3. A surface condenser comprising an inlet 90 for steam, a tube nest divided into a plurality of groups of tubes, water boxes communicating with each group of tubes, piping to circulate cooling water through each group of tubes, valves in said piping to regulate the 95 flow of water through any group of tubes, a pump connected to said piping adapted to withdraw water from any group of tubes, and means to maintain a vacuum in a group of tubes from which water has been excluded. 100
